UNITED STATES PATENT OFFICE

WILLIAM FREEGARD, OF ELIZABETH, NEW JERSEY, ASSIGNOR TO THE BARBER ASPHALT COMPANY, OF PHILADELPHIA, PENNSYLVANIA, A CORPORATION OF WEST VIRGINIA

SURFACE COVERING AND METHOD OF MAKING THE SAME

Application filed January 14, 1928. Serial No. 246,712.

This invention relates to a surface covering of the type applicable to the roofs or walls of buildings and to the shingles constituting such covering and a method of making the same.

The use of shingles of felt impregnated with bitumen or tar permits the construction of very satisfactory roofs or walls which are rain and windproof, such shingles being 10 cheaper and more easily applied than the rigid slate or wooden shingles formerly much used. Because of their lightness and flexibility, however, they are apt to be raised and freed from the foundation by wind unless 15 securely fastened in position. One object of the present invention is, accordingly, the provision of an improved surface covering in which such shingles are securely held in place.

20 Another object of this invention is the provision of an improved shingle having the capacity for covering a maximum area when built into a surface covering of the type mentioned above.

25 A further object is the provision of a method of constructing shingles from a strip of sheet material with the maximum economy of material and minimum of labor.

Other more specific objects and advantages 30 will be apparent from the following description read in conjunction with the accompanying drawing, in which:

Fig. 1 is a view of a surface covering formed by the assembly of one form of the 35 improved shingles;

Fig. 2 is a view of a portion of a strip of sheet material illustrating the method of cutting shingles of the type shown in Fig. 1 therefrom;

40 Fig. 3 is a plan view of one of the shingles shown in the preceding figures;

Fig. 4 is a plan view of a modified form of shingle; and

45 Fig. 5 is a view similar to Fig. 2 illustrating the method of cutting still another modification of the improved shingle from a strip.

Referring first to Figures 1, 2, and 3, one form of the improved shingle is designated by the numeral 2. This shingle is of substantially square shape, having four prin-

cipal edges arranged at right angles and equally spaced in square form and, when assembled as shown in Fig. 1, appears as a square shingle with the lower corner truncated. When diagonals of the shingle are 55 hereinafter referred to it will be understood that the diagonals of the parallelogram formed by the principal edges produced are meant. The shingle itself, as cut from a sheet of material, differs from square shape 60 in having a tab at its lower corner and a cut away side corner. The tab which is indicated at 4 is of rectangular shape, having a straight bottom edge 6 and side edges 8, and is adapted to be bent beneath the body portion of the shingle about a line defined by the inner ends of a plurality of slits 10 formed in the shingle. It will be noted that tab 4 is symmetrical about a diagonal through corner 12 of the shingle. 65

One of the side corners of the shingle 2 is cut away, as shown in Fig. 3, forming an edge 16 extending parallel to the diagonal through corner 14 and edges 18 and 20 extending parallel to the diagonal through corner 12. The construction and purposes of these edges will be apparent hereafter during the description of the assembly of the shingles. 70

The shingles described above may be made 80 from a strip 22 of impregnated felt or the like having, if desired, a mineralized surface. Horizontal cuts 24 and 26 are made from opposite edges of strip 22 and further cuts are made down the center of the strip and 85 to form the tabs as shown in Fig. 2. As shown in that figure, opposite shingles are relatively displaced to a slight degree in the direction of the length of the strip whereby the contacting tabs are thrown out of diagonal alignment sufficiently to form a shoulder in 90 each shingle by edges 16 and 20.

Although strip 22 is shown as having a width just twice that of a shingle measured 95 between opposite edges thereof, it will be obvious that a wider strip may be used from which four, six or more rows of shingles might be cut in a similar manner.

Referring now to Fig. 1 in which a number of shingles are shown assembled to form 100

a roof or wall covering, it will be seen that the shingles are laid in horizontal rows with tabs downwardly disposed. A shingle 28 which overlaps two shingles 30 and 32 of the next lower row has its tab 4 turned beneath the adjacent corners of shingles 30 and 32, the lower sloping edges of shingles 30 and 32 entering slots 10 of shingle 28 whereby a secure engagement of the lower corner of shingle 28 is obtained. The shingles are secured to the foundation by suitable nails 34 or the like.

The object of the relative displacement of the opposite shingles during cutting from strip 22 will be apparent if the result obtained by cutting them directly opposite each other is considered. If they are so cut, no edge 16 will be formed and edges 18 and 20 will be aligned as a single edge. If the shingles thus produced were laid as shown in Fig. 1, it would be necessary to place adjacent shingles 30 and 32 closer together than they would be if corner 14 of shingle 30 touched the corner which would be produced by extending the upper and lower principal edges at the left of shingle 32. If they were not so positioned, the right hand end of tab 4 of shingle 28 would fail to engage shingle 32. On the other hand, by cutting the shingles in the manner shown, there is formed a projection between edges 16 and 20 which is engaged by tab 4 even though the shingles 30 and 32 are placed further apart than the positions with their corners touching, (the corner of shingle 32 being defined by the meeting of the produced edges as described above). By cutting the shingles as described, an economy of material is obtained since not only is there practically no waste in a strip of material from which they are cut, but also a smaller number of shingles is required to cover a given area by reason of the possibility of increasing the spacing.

But cutting shingles 2 as shown in Fig. 2, it will be noted that edge 16 is formed somewhat above the diagonal through the opposite corner 14. It is desirable that the workman who places the shingles in position should have some means by which he could gauge the proper positioning of adjacent shingles. A convenient method of accomplishing this result is to have edge 16 formed on the horizontal diagonal of the shingle so that the corner 14 of a shingle 30 would be aligned with edge 16 of an adjacent shingle 32. Edge 16 may be cut down to the diagonal by a separate cutting operation or by a cutting operation simultaneous with the cutting of the shingles from strip 22, such simultaneous cutting being preferably accomplished without waste of material or formation of scraps in the manner indicated in connection with a slightly different type of shingle in Fig. 5.

In Fig. 5 is shown the method of cutting

shingles of lozenge shape rather than square shape from a strip of material, parallel cuts 36 and 38 forming other than right angles with the edges of the strip being made therein, the opposite shingles in this modification also being relatively displaced in the lengthwise direction of the strip. In this modification shoulders 42 are formed along the diagonals of the shingles, the tabs accordingly having their lower edges formed by sloping portions 44 and portions 46 extending parallel to the diagonals.

A shingle having its adjacent principal edges intersecting at right angles and having a tab and shoulder similar to those in Fig. 5 is shown in Fig. 4, the corresponding parts being designated by the same reference numerals. The shingles shown in Figs. 4 and 5 may be conveniently placed with the right hand corner of one aligned horizontally with edge 42 of an adjacent shingle.

While the lozenge shaped shingle is shown only with an unsymmetrical tab, it will be obvious that such shingle may be formed with a tab such as shown in Fig. 3. Furthermore, although during the cutting from a strip it is desirable that the opposite shingles be displaced as shown, it is clear that they may be formed directly opposite each other, with, however, a sacrifice of the advantages set forth. Other modifications which do not depart from the spirit of the invention will also be apparent and within the scope of the appended claims.

Having now fully described my invention, what I claim and desire to protect by Letters Patent is:—

1. The method of cutting shingles of substantially parallelogram shape with tabs at corners thereof from a strip of material including forming transverse and longitudinal cuts in the material and further cuts to form the tabs, diagonally disposed shingles being out of diagonal alignment with each other and the tabs of the shingles so diagonally disposed abutting each other.

2. The method of cutting shingles of substantially parallelogram shape with tabs at corners thereof from a strip of material including forming transverse and longitudinal cuts in the material and further cuts to form the tabs, diagonally disposed shingles being out of diagonal alignment with each other and the tabs of the shingles so diagonally disposed abutting each other, each shingle having a truncated corner with an edge formed along a diagonal thereof.

3. A shingle comprising a body portion of substantially quadrilateral shape having a tab at one corner thereof adapted to be folded beneath the body portion of the shingle, an adjacent corner of the body portion being truncated to form a stepped edge, the part of said edge nearest the tab being extended farthest outwardly and outlining a

projection on said body portion, the said projection being adapted to engage with the tab of a similar shingle of a superjacent course."

5 4. A shingle comprising a body portion of substantially quadrilateral shape having a tab at one corner thereof adopted to be folded beneath the body portion of the shingle, a pair of slits being formed in the sides of the
10 shingle at the ends of the fold line of the tab, and an adjacent corner of the body portion being truncated to form a stepped edge, the part of said edge nearest the tab being extended farthest outwardly and outlining
15 a projection on said body portion, the said projection being adapted to engage with the tab of a similar shingle of a superjacent course.

In testimony of which invention I have
20 hereunto set my hand, at Maurer, N. J., on
this 3rd day of January, 1928.

WILLIAM FREEGARD.
